UNITED STATES PATENT OFFICE

ALPHONSO S. COMSTOCK, OF EVANSTON, ILLINOIS

NONMETALLIC TRUSS

Application filed April 7, 1930. Serial No. 442,172.

My invention relates to surgical apparatus, and more particularly to adjustable trusses.

The common truss in use at the present time is formed generally of metal with suitable covering, comprising a single circular, or oval shaped steel spring having a suitably shaped pad at the extremities of the spring adapted to bear against the ruptured portion 10 of the abdomen. It is well known that the wearing of a truss is generally disliked and in many instances, persons requiring the benefit of a truss refrain from the use of the same.

A further objection to the common truss 15 lies in the fact that frequently no provision is made for the various movements of the body of the wearer in carrying out his ordinary occupation. For instance, the rupture is in many trusses totally or partially unsupported when the wearer leans over, or stands in any but a practically erect posture. The pressure is maintained in a standing or sitting position and is caused to vary by the non-adaptiveness of the truss to 20 normal positions. Thus it is frequently inconvenient and painful for a truss wearer to move about in a normal manner. A further objection to the common truss is that it 25 very frequently shifts its position during body movements, and may be discovered to be removed from the rupture and performing no service whatever.

An object of my invention is to enable the user to wear the same in a bath without danger of deterioration or injury thereof due to 30 the moisture etc.

However, the truss of my invention is intended to eliminate all of the above and many other common objections made by truss wearers.

An object of my invention is to provide a truss having a leg and waist band of pure rubber, thus maintaining an even fit yet not as uncomfortable as a metal truss. In addition, the use of uncovered rubber serves to prevent, to a marked degree, any shifting of the straps when the pad has been placed over the rupture.

A further object of my invention is to provide a rupture pad that eliminates any pos-

sibility of the shifting thereof from the rupture during ordinary body movement of the wearer. In addition, the pad of my invention serves to maintain an even pressure against the rupture in any position of the body. The advantage is made possible by the use of a number of superposed layers of sheet rubber, formed in a suitable size and shape for the purpose desired.

A further object of my invention is to 60 provide means on the truss for affecting the adjustment thereof to suit the particular anatomical configuration of the user.

My invention will be more readily understood by reference to the accompanying 65 drawings, in which

Fig. 1 is a perspective view showing the application of the truss of my invention to the body of a wearer;

Fig. 2 is a vertical sectional view of the truss-pad of my invention taken on the lines 2-2 of Fig. 3;

Fig. 3 is a horizontal sectional view of the pad of my invention;

Fig. 4 is a plan view partly in section of 75 the rear adjusting means.

By reference to the accompanying drawings, it will be seen that my invention comprises a truss pad, generally indicated at 10, supported by a waist band 11, and leg strap 12, the straps 11 and 12 are preferably of pure rubber, to provide a measure of non-slipping contact with the body. The leg strap 12 is preferably adjustably secured to the waist-band at the back by means of 80 the snaps 14, or other suitable means, as best shown in Fig. 4.

The truss pad of my invention is formed of substantially oval shape in cross section and having side faces of suitable area. The pad is formed of a number of superposed layers of rubber sheeting, *a*, *b*, *c*, and *d*, joined at the lower end, presenting the form of a cone. The upper end of the pad is open, the outer face thereof being joined to the waist-band 11. If desired, a flap 13 may be secured to the pad face adjacent to the body to protect the body from the chafing of the top edges of the pad when bending over, for 95 instance.

In the form herein illustrated, which has been found more desirable, the top is open and the bottom closed. A number of apertures 15 are punched in the sides of the pad 5 near the bottom for the purpose of draining water when the device is worn while bathing.

When applied to the body of a ruptured wearer, the pad is found to assume the form shown by the dotted lines in Fig. 3. That is, 10 the waist-band 11 is placed on the outside of the pad and the inner face bears against the rupture. It will thus be seen that the pad readily assumes the general contour of the rupture. The pad being formed of a non-slipping material, such as rubber, it will be 15 found that the moving of the pad away from the desired position is almost impossible.

By reason of the various layers of sheet rubber forming the pad, a certain even pressure 20 will be constantly applied to the rupture and additional layers can be formed thereon to suit the particular requirements, if desired.

Obviously the truss of my invention is well 25 adapted for the purpose for which it is intended. In many instances one requiring a truss experiences exceeding discomfort from the normal presence of the clothes worn, and it is next to impossible to stand the confining pressure of a steel truss. However the truss 30 herein disclosed is so constructed to eliminate any abnormal binding against the body, thereby permitting the use thereof by the most sensitive persons. The pad provides an even pressure at the proper point and will 35 not shift out of place.

It is conceivable that one skilled in the art may conceive of numerous modifications and variations in the device herein disclosed and 40 I do not wish to be limited except as indicated in the appended claims.

I claim:

1. A device of the class described comprising 45 an adjustable, resilient waist band, a truss pad secured to said band, said pad being of substantially conical shape, the top end thereof being open, and being formed of a plurality of concentric, superposed layers of resilient material, and an adjustable, resilient leg strap adapted to join the lower end 50 of the pad and the waist band at the opposite side.

2. A device of the class described, comprising 55 an adjustable, resilient waist band, a truss pad secured to said band, said pad being of substantially conical shape, the top end thereof being open, and being formed of a plurality of concentric superposed layers 60 of resilient material, an adjustable resilient leg strap adapted to join the lower end of the pad and waist band at the opposite side, the free side of said pad being adapted to bear 65 against and encompass a rupture, and means associated with the free side of said pad for

covering the top edge thereof when the same is compressed.

In testimony whereof I have affixed my signature.
